Specification of Letters Patent. Patented Jan. 17, 1922.

Application filed January 21, 1918, Serial No. 213,038. Renewed June 15, 1921. Serial No. 477,862.

To all whom it may concern:

Be it known that I, HARRISON H. EATON, a citizen of the United States, residing at Beverly, in the county of Essex and Commonwealth of Massachusetts, have invented certain Improvements in Presses, of which the following description, in connection with the accompanying drawings, is a specification, like reference characters on the drawings indicating like parts in the several figures.

This invention relates to presses in which the presser members are relatively movable in a direction to effect a pressing operation and also in other directions so as to bring the members into different pressing relations to work preferably carried by one of said members.

In particular the invention relates to presses of the type in which a pressure-applying member is movable into various operative relations to its bed. For the sake of illustration the invention is shown embodied in a press of the type mentioned which is especially adapted for forcing a die through sheet material, such as leather, for the purpose of dieing out from the material blanks for manufacturing uses, although it will be understood that the invention is not limited to application to presses of this character.

In presses of the type above referred to, as heretofore constructed, the pressure-applying member has usually been arranged to be moved by the operator into and out of the desired relation to the pressure-receiving member or bed. It is an object of the present invention to provide improved power means for moving the pressure-applying member, the said means being characterized by simplicity in construction and operation and economy in manufacture. This arrangement of power means for moving the presser members will prove less fatiguing to the operator and will enable him to locate the pressure-applying member over the selected portion of the bed with the same accuracy and with greater ease than that which accompanied the positioning of the pressure member by hand. In the preferred form of the invention the power means for shifting the presser members to bring them into different relations to each other is so constructed and arranged as to be under the control of the operator at all times.

Conveniently, the power means for causing relative movements of the presser members into and out of operative relations with each other is controlled by manually operable means. Preferably the means last mentioned is connected with mechanism which may be operated at the will of the operator to determine the time at which relative pressure-applying movement of the presser members shall take place in carrying out those operations upon the work for which the machine is designed.

In the particular construction herein disclosed, means are provided for causing disconnection of the power means, which moves the presser members laterally relatively to each other, from said presser members, said disconnection taking place as the machine is thrown into operation to cause the application of pressure. This arrangement adds to the ease and rapidity with which the machine may be operated. Were it not for this construction, the operator would have to disconnect said power means by a conscious effort properly timed with respect to the other operations in order to secure the best results. In a practical form of the invention, the means for causing disconnection of the power means so that the lateral relative movement of the presser members is discontinued, is so constructed and arranged as to be operable by the manually operable means for controlling said power means.

Other features of novelty which contribute to the carrying out of objects of the invention hereinbefore enumerated or to other objects of the invention which will be apparent from a consideration of the disclosure of the invention in the specification and drawings will either be pointed out in the following detailed description or included in the claims, or attention will be directed to them both in the specification and claims, and it will be understood that it is my intention to cover by claims in this application all that is herein disclosed of my invention.

On the accompanying drawings which represent one embodiment of the invention, Fig. 1 is a view in side elevation of a clicking machine disclosing one embodiment of my invention;

Fig. 2 is a plan view from above with

parts broken away to show more clearly the connection between the operating means and the pressure member; and

Fig. 3 is a detail view on an enlarged scale taken along the line 3—3 in Fig. 1 looking in the direction of the arrows.

As illustrated the invention is shown embodied in a machine of the type disclosed in the patent to Arthur Bates, No. 921,503, granted May 11, 1909. This machine comprises an approximately C-shaped frame member 4 having bearings 6 for a vertical post 8 carrying a presser member 10 fixedly secured thereto. The other presser member 12 is ordinarily termed a cutting bed for the reason that the stock is supported upon this member which receives the thrust of the die 13 used in cutting out blanks from the stock. Inasmuch as the pressure surface of the upper presser member is very much less than that of the lower presser member or cutting bed it is necessary to mount the presser members for relative movement laterally of each other, in order that the die may be operated upon when located at widely separated points on the bed. In this case the upper presser member is movably mounted, as the post 8 is rotatably carried in the bearings 6. In order to reciprocate the upper presser member toward and from the cutting bed, connections 14 are provided between the post and the main shaft 16 mounted in the base of the machine frame, said connections comprising a pivoted and swiveled link, all as disclosed in the patent referred to above.

It has been the practice heretofore for the operator to swing the upper pressure member into selected position manually, a handle having been provided on the presser member for this purpose. According to my invention, power means are provided for carrying out this operation, thus rendering the operation of the machine less fatiguing to the operator, the construction being such, moreover, that the presser member may be brought into its selected position with the same accuracy as when it was positioned by hand. This mechanism for moving the presser member laterally with respect to the cutting bed comprises a shaft 18 which is mounted in bearings 19 and 20 for rotary movement therein and also for endwise movement. Connected to the end of the shaft 18 is a gear wheel 22 in constant mesh with a second gear 24 mounted on a stub shaft in the same bracket 26 which carries the shaft 18. The gear 24 has a much wider face than that of gear 22 so that the two gears, 22 and 24, remain in mesh in whatever position the shaft may be adjusted. Gear 24 is driven from a pulley 28 fixed to the stub shaft, said pulley being driven in turn by a belt 30 whose other end engages a pulley 32 fixed to the loose power

pulley 34 on the main shaft 16. It will thus be seen that the shaft 18 is driven continuously from the power pulley 34 by the connections above described. Surrounding the shaft 18 inside of the bearing 19 is a sleeve which carries rotatably thereon two bevel gears 36 and 38. These gears are held constantly in mesh with a bevel gear 40 horizontally positioned between them, said gear 40 being fixedly attached to the upper end of a shaft 42 shown in dotted lines in Fig. 1 as mounted in an extension of the bracket 26. Mounted upon the lower end of shaft 42 is a gear wheel 44 which is constantly in mesh with a large gear 46 secured to the post 8. Because of the fact that the post is mounted adjustably in its bearings in order to position the upper presser member adjustably with respect to the cutting bed, and is mounted moreover for vertical reciprocation in the said bearings 6, it follows that one of the gear wheels 44 and 46 must have a much wider face than the other in order that the gear wheels may remain in mesh in all positions of adjustment of the post. In order to drive the gears 36 and 38 selectively there are provided friction clutches 48 and 50 fixedly secured to the shaft 18, the arrangement being such that when the shaft 18 is in a certain position, hereinafter designated as its neutral position, neither of the friction clutches is engaged with its corresponding bevel gear. When neither clutch is engaged with its respective gear, the presser member is stationary. If, however, the shaft 18 be moved to the right in Fig. 2, the friction clutch 50 will engage the bevel gear 36 thus causing the horizontal gear 40 to be revolved in one direction to turn the post and the presser member 10 laterally with respect to the cutting bed whereas with the shaft 18 shifted to the left in Fig. 2 the other friction clutch 48 will be engaged with its bevel gear 38 to cause turning of the presser member 10 in the opposite direction. Shifting of the shaft 18 axially is provided for by means of a member 52 having a bifurcated arm 54 carrying rollers 56 which engage in a circular groove in a collar 60 fixed to the shaft 18. As shown in Fig. 1, the bracket 26 has an extension toward the front of the machine which carries a vertical shaft 62 at the upper end of which member 52 is fixedly secured. On the lower end of this same shaft there is fixedly attached a member 64 having connected therewith a bell-crank 66 provided with a handle 68. It is obvious that movement of the handle 68 to the right or left in Fig. 2 will result in a shifting of the shaft 18 in a direction axially thereof so as to cause the engagement of one of the friction clutches with its corresponding gear wheel to cause the swinging of the presser member in the desired direction. The mem-

ber 52 has a second arm 70 extending forwardly into a space in an upward extension of the forward end of the bracket 26. Bearing upon each side of the forward end of the arm 70 are two springs 72 which can be adjustably tensioned by screw threaded members 74, the said springs exerting just sufficient pressure on the arm 70 to maintain the shaft 18 in neutral position. With the shaft 18 in neutral position, the presser member 10 may be moved by hand without the intervention of the power means described above. An advantage of the friction type of clutch in the operating mechanism just described resides in the fact that it may be used as a brake. Thus the presser member under motion in a direction toward or from operative position may not only be instantaneously disconnected from the power means which is giving it motion but may be promptly checked by shifting to the other clutch which, as stated, will act as a brake. Moreover, the cone type of friction clutch permits of a gradual or rapid application of the brake and hence the operator may feel safe in causing the presser member to move as rapidly as he desires since it may be stopped in the desired location by the application of the brake, which may be either of the friction clutches 48 and 50.

The handle 68 has another function than that described above, namely, that of throwing the machine into operation in order to cause a reciprocation of the pressure member to apply pressure to the die in cutting out blanks from the stock. The structure provided for the purpose of carrying out this operation comprises the bell-crank 66, which is pivoted to member 64 for movement in a vertical plane and is provided with an upright arm 75 connected by a rod 76 with an arm 78 fixedly secured to a horizontally extending rod 80 having at its other end a second arm 82 extending from the rod practically at a right angle to the arm 78. The handle 68 is maintained in its raised or normal position by a light spring 81 surrounding rod 80 and bearing against arm 78. Connected to the arm 82 is a rod 84 the lower end of which operates the clutch control mechanism on the main shaft of the machine, said clutch mechanism comprising a clutch of the one-revolution non-repeating type. Hence, when the handle 68 is depressed the clutch mechanism will be operated to connect the power pulley 34 to the shaft 16 to cause a single reciprocation of the upper presser member 10.

A forwardly extending arm 86 of the bracket 26 carries a plate 88 which is slotted, the edges of the slot being beveled to present inwardly slanting surfaces 90. Carried by the arm 66 of the bell-crank there is a member 92 having a wedge shaped end, the obliquely directed surfaces 94 of which are designed to engage selectively with one or the other of the slanting surfaces on the slotted plate, the arrangement being such that on depression of the handle 68 the same will be caused to move to such a position by the engagement of the surfaces aforesaid that the shaft 18 will be shifted to neutral position. Were it not for this construction, the operator would have to make a conscious effort to move the shaft to neutral position when he had brought the presser member directly over the selected position for the die on the cutting bed so that the lateral movement of the said presser member might be terminated, and then by a distinct movement of the handle 68 depress the same to cause the pressure-applying operation of the presser member. By the construction shown the operator moves the handle 68 laterally to cause the power means to move the pressure member over the selected position on the cutting bed and when the member has arrived at this position he immediately depresses the handle, whereupon the presser member is caused to descend in its pressure-applying operation, a brake member 96 being depended upon to terminate the lateral movement of the presser member so that the die is forced by a direct blow through the work. For a complete disclosure of the brake mechanism indicated at 96 reference should be had to the patent to Harrison H. Eaton, No. 1,004,757, granted October 3, 1911, it being understood that the springs, shown in connection with the brake mechanism, which operate to return the presser member to one side of the bed, are operative in the present construction.

The manner of using this machine will be sufficiently evident from the preceding description and from the fact that, in general, well-known features of operation are involved. Ordinarily the presser member 10 will be swung away to one side to uncover completely the cutting bed 12, in order that the operator may have an uninterrupted view of the stock and the best possible conditions as to light in placing his dies upon material to be cut into blanks. When a die has been placed, the operator grasps the handle 68 and moves it to the left in Fig. 2 to cause the power means to move the presser member 10 over the die in its selected position. When the pressure member arrives over the die, the operator immediately depresses the handle thereby causing the pressure-applying movement of the presser member. Obviously the handle 68 constitutes a single means for controlling the lateral and the pressure-applying movements of the presser member. It will be observed, moreover, that the presser member is at all times under the control of the oper-

ator. After the pressure member rises from its operative stroke, the operator moves handle 68 to the right to cause the power means to move the presser member to one side 5 of its position over the die or to a position to which the cutting bed is completely uncovered. Since the power means for moving the upper presser member laterally is at all times under the control of the operator, the said means may be operated to 10 overcome the inertia of the presser member in starting it from rest and to give it an impulse to move in the desired direction without moving it the whole distance to operative 15 position. In other words, the power means may start the presser member from rest and cause it to be moved only a portion of the way to operative position and then be disconnected, thus permitting the 20 presser member to continue in motion under its acquired momentum and under the manual control of the operator. From this viewpoint an important feature of the invention comprises the provision of means for 25 overcoming the inertia of the movable presser member in starting it from a position of rest to move it toward or from operative position.

Having described my invention, what I 30 claim as new and desire to secure by Letters Patent of the United States is the following:

1. A machine of the class described, comprising co-operating presser members arranged for relative swinging movement in amounts determined at the will of the operator to bring them into different operative relations to each other, and power means at all times under the control of the operator 40 for causing said relative swinging movement.

2. A machine of the class described, comprising co-operating presser members arranged for relative movement in amounts 45 determined at the will of the operator to bring them into different operative relations to each other, and power means for causing said relative movement, said means comprising mechanism constructed and arranged 50 to be at all times under the control of the operator for disconnecting the power means to terminate said relative movement, the construction and arrangement being such that the power moved presser member may 55 also be manually moved relatively to the other presser member.

3. A machine of the class described, comprising co-operating presser members arranged for relative movement in amounts 60 determined at the will of the operator to bring them into different operative relations to each other, and power means at all times under the control of the operator for causing relative swinging movement of the members 65 out of their selected operative position.

4. In a cutting machine, a cutting bed for supporting the stock, a movable die, a pressure member movable from and into operative position over the bed, power means for moving the pressure member into various operative relations to the bed, means for causing relative reciprocating movement of the pressure member and bed to force the die through the work, and means under the control of the operator for causing the operation of said power means, the arrangement being such that the operator-controlled means is in direct control of said power means throughout the movement of the pressure member into its selected operative position. 80

5. A machine of the class described, comprising co-operating presser members arranged to be mounted so that one of the members can be swung into and out of vertical alignment with the other member, power means at all times under the control of the operator for swinging one of the members relatively to the other, and means for causing a relative reciprocatory movement of the pressure members to operate 90 upon the work.

6. A machine of the class described, comprising co-operating presser members arranged to be mounted so that one of the members can be swung into and out of vertical alignment with the other member, power means at all times under the control of the operator for swinging one of the members relatively to the other, means for causing a relative reciprocatory movement 95 of the presser member to operate upon the work, and braking means for checking the swinging movement of the movable presser member, said braking means being operative after the initiation of the said reciprocatory 100 movement.

7. A machine of the class described, comprising co-operating presser members arranged for relative movements in amounts determined at the will of the operator to 110 bring them into different operative relations to each other, power means at all times under the control of the operator for effecting the relative movements referred to, and means, having an element in common with the first-mentioned means, for causing a relative reciprocatory movement of the pressure members to operate upon the work. 115

8. In a machine of the class described, the combination with co-operating presser members relatively movable into different pressing relations to stock carried by one of said members, of means for effecting a relative pressure-applying movement of said members after they have been brought into 120 a selected pressing relation to each other, and power means at all times under the control of the operator for effecting a relative movement of said members out of the selected pressing relation after their relative 125 130

- pressure-applying movement and in a direction transverse thereto, the construction and arrangement being such that the power moved presser member may also be manually 5 moved into or out of operative position.
9. In a machine of the class described, the combination with a bed, of a pressure-applying member movable into various operative relations to said bed, means for actuating said pressure-applying member to apply pressure after a relative movement into a selected operative relation, and power means at all times under the control of the operator for returning said pressure-applying member to its original position after such actuation.
10. A machine of the class described, having in combination, a bed, a pressure-applying member movable into various operative 20 positions over said bed, means for actuating said pressure-applying member to apply pressure when it has come into a selected operative position over said bed, and power means at all times under the control of the operator for moving said pressure-applying member out of the selected operative position after such actuation.
11. In a machine of the class described, the combination with a bed, a die movable 30 over said bed, and a pressure-applying member movable over said bed into operative position above said die, of means for actuating said pressure-applying member to apply pressure to said die, and power means at all times under the control of the operator for moving said member out of its operative position over said die after such actuation.
12. A machine of the class described, 40 comprising a bed, a die movable over said bed at the will of the operator into various selected positions, a pressure-applying member movable into operative position over said die, and power means at all times under the control of the operator for moving said member any desired distance out of operative position over said die.
13. In a machine of the class described, the combination with a bed and a die movable 50 over said bed, of a pressure-applying member movable into operative position above said die, means for actuating said pressure-applying member to apply pressure to said die after a movement into operative position, and power means at all times under the control of the operator for returning said pressure-applying member to its original position after such actuation.
14. In a machine of the class described, 60 the combination with a bed, of a pressure-applying member movable into various operative positions over said bed, power means for moving said pressure-applying member, means for moving said pressure-applying member relatively to said bed to apply pres-
- sure, and means mounted over the front of the bed and having limited movement into position to cause the actuation of said power means, the construction and arrangement being such that said means must be held by 70 the operator in said position to maintain said power means in operation and thus determine the position over the bed at which pressure shall be applied.
15. In a machine of the class described, 75 the combination with a bed, of a pressure-applying member movable into various operative positions with respect to said bed, and means at all times under the control of the operator for moving said pressure-applying member to a selected position over said bed, for actuating it to apply pressure, and for returning it to its original position.
16. In a machine of the class described, 80 the combination with a bed, of a pressure-applying member movable into various operative positions over said bed, means for moving said pressure-applying member to the desired position over the bed at which it is desired to apply pressure, and for actuating said pressure-applying member to apply pressure at said predetermined position, and power means at all times under the control of the operator for returning said pressure-applying member to its original 90 position.
17. In a machine of the class described, 95 the combination with a bed, of a member co-acting therewith to apply pressure over a limited area of said bed of selected location, and power means at all times under the control of the operator for moving said member to said selected location.
18. In a machine of the class described, 100 the combination with a bed, of a member co-acting therewith to apply pressure over a limited area of said bed of any selected location, power means for moving said member to said selected location, together with means at all times under the control of the operator for causing the operation of said last-mentioned means.
19. In a machine of the class described, 110 the combination with a bed and pressure member movable thereover into different selected operative relations thereto, of a shaft and connections between said member and shaft at all times under the control of the operator for moving said member to the selected place over the bed at which pressure is to be applied.
20. In a machine of the class described, 120 the combination with a bed and a pressure member movable thereover, of a shaft, connections between said member and shaft for moving said member to the place over the bed at which pressure is to be applied, and means constructed and arranged to be moved by the operator into position for initiating movement of the pressure member and to be 130

held by the operator in position to cause continued movement of the presser member, said pressure member continuing to move only so long as the said means is held by the 5 operator in said position whereby said means determines the place over the bed at which pressure is to be applied.

21. In a machine of the class described, the combination with a bed and a presser 10 member movable thereover, of a shaft, connections between said member and shaft for moving said member to the selected place over the bed at which pressure is to be applied, and means constructed and arranged 15 to be held by the operator in position to determine the action of said connections, the construction and arrangement being such that said connections are controlled by said means only while said means is held by the 20 operator in said position.

22. In a machine of the class described, the combination with a bed and a presser member movable thereover, of a power driven shaft movable also under force exerted by the operator, operating connections 25 between said member and shaft for moving said member to the selected place over the bed at which pressure is to be applied, and means for moving said member relatively to 30 said bed to exert pressure upon work on the bed.

23. In a machine of the class described, the combination with a bed, of a member co-acting therewith to apply pressure over 35 various parts thereof, and power operated means at all times under the control of the operator for moving said member into operative position over a selected part of said bed at which pressure is to be applied.

40 24. In a machine of the class described, the combination with a stock supporting bed presenting a surface with various portions of which a stock cutting die may co-operate in dieing out stock, of die-pressing 45 means movable into and out of different operative positions over said die and bed, and power means at all times under the control of the operator for effecting such movements of said pressing means.

50 25. In a machine of the class described, the combination with a horizontal bed, a vertically reciprocating column and a radial arm carried by said column and rotative into different relations to said bed, of power 55 means comprising a lever for imparting to said radial arm rotative movements varying in amount in accordance with the length of time the lever is held in power-means-controlling position.

60 26. A machine of the class described, having in combination, a bed, a die movable over said bed, a presser member movable from a position at one side of the die into a position over the die wherever located on 65 the bed, mechanism for moving the presser

member toward the bed to force the die through stock supported on the bed, and power means directly under the control of the operator and constructed so that the operator may determine the time and duration of operation of said power means for moving the presser member out of operative position over the die to a selected position at one side of the die after the pressing operation. 70

75 27. A machine of the class described, having in combination, a bed, a die movable over said bed, a presser member laterally movable over said bed into and out of position over said bed into and out of position over the die wherever located on the bed, mechanism for moving the presser member toward the bed to force the die through stock supported on the bed, and power means at all times under the control of the 80 operator for effecting the lateral movements of the presser member.

85 28. A machine of the class described, having, in combination, a bed, a die movable over the bed, a presser member laterally movable over the bed into position over the die wherever located on the bed, controlling means also laterally movable over the bed, and means under control by said controlling means for effecting the lateral movement of 90 the presser member, said controlling means being arranged to operate throughout the lateral movement of the presser member.

95 29. The combination with a bed and a presser member movable thereover into different selected operative relations thereto, of a power-driven shaft movable also by force exerted by the operator, and connections between said member and shaft for moving the member to the selected place 100 over the bed at which pressure is to be applied. 105

30. The combination with a bed and a presser member movable thereover into different selected operative relations thereto, of a shaft directly under the control of the operator, and connections between said member and shaft for moving the member to the selected place over the bed at which pressure is to be applied and for moving 110 the member away from said selected place, the construction and arrangement being such that the operator through said shaft may determine the extent of movement of the presser member in one direction independently of the extent of movement in the other direction. 115

120 31. The combination with a bed and a presser member movable thereover into different selected operative relations thereto, of a shaft movable by force exerted by the operator, clutches connected directly to said shaft, and connections between said member and shaft controlled selectively by said clutches, said connections being operated 125 130

from the shaft for moving the member to the selected place over the bed at which pressure is to be applied and for moving the member away from said selected place.

5 32. The combination with a bed and a presser member movable thereover into different selected operative relations thereto, of an axially shiftable shaft, connections between the shaft and the presser member 10 for moving the latter to a selected place over the bed and away from said selected place, and a lever under the control of the operator for shifting the shaft to determine the direction of movement of the presser 15 member.

33. The combination with a bed and a presser member movable thereover into different selected operative relations thereto, of an axially shiftable shaft arranged to be 20 continuously driven from the source of power, clutches connected to said shaft, and connections between the shaft and pressure member operable selectively by means of said clutches, the arrangement being such 25 that there is a neutral position of the shaft wherein neither clutch is engaged to drive the connections whereby the presser member may remain stationary in any desired location.

30 34. The combination with a bed and a presser member movable thereover into different selected operative relations thereto, of a shaft, clutches surrounding said shaft, connections between the shaft and the member 35 operable selectively by means of said clutches, and a lever for shifting the clutches to bring one or the other into co-operation with said connections to cause the presser member to be moved over the bed or away 40 therefrom as desired.

35. In a machine of the class described, presser members mounted for movement laterally relatively to each other, power means at all times under the control of the operator 45 for causing such movement, and means for disconnecting said power means as the machine is thrown into operation to effect a pressure-applying operation of the presser members.

50 36. In a machine of the class described, presser members mounted for movement laterally relatively to each other, power means at all times under the control of the operator for causing said movement, manually operable means for controlling said power means, and means for disconnecting said power means from the presser members as the machine is thrown into operation to effect a pressure-applying operation.

60 37. In a machine of the class described, presser members mounted for movement laterally relatively to each other, power means at all times under the control of the operator for causing said movement, manually operable means for determining the duration

of the operation of said power means, and means co-operating with the manually operable means for disconnecting the power means from the presser members as the machine is thrown into operation to effect a 70 pressure-applying operation.

38. In a machine of the class described, presser members mounted for movement laterally relatively to each other and for relative movement toward and from each other 75 in a pressure-applying operation, power means for causing relative movements of the presser members in the different directions, a single means at all times under the control of the operator for controlling the 80 power means to effect successively at the will of the operator relative movements of the members in the several directions, and means for disconnecting the presser members from the power means for causing lateral movement of the presser members relatively to each other, said means being arranged to operate prior to the pressure-applying operation of the presser members. 85

39. In a machine of the class described, 90 presser members, mounted for relative movement in a direction laterally of each other and in a direction toward and from each other in a pressure-applying operation, power means for causing the relative lateral 95 movement of the presser members, power means for causing the pressure applying movement of the presser members, manually operable means for controlling each of the power means aforesaid, and means for disconnecting from the presser members the power means for causing relative lateral movement of the same, said disconnecting means being arranged to act as the second-mentioned power means is thrown into operation. 100

40. In a machine of the class described, presser members mounted for movement laterally relatively to each other, power means at all times under the control of the operator 110 for causing said movement, power means for causing relative pressure-applying movements of the presser members, manually operable means for determining the time of operation of each of the power means, and means for disconnecting the first-mentioned power means from the presser members prior to the operation of the second-mentioned means. 115

41. The combination with a bed and a 120 presser member movable thereover into different selected operative relations thereto, of a shaft, clutches surrounding said shaft, connections between the shaft and the member operable selectively by means of said 125 clutches, a lever for shifting the clutches to bring one or the other into co-operation with said connections, said lever being operable also to throw the machine into operation to cause the pressure-applying move- 130

ment of the presser member, and means for positioning the clutches so that neither are operatively engaged with said connections, said means acting as the lever is depressed 5 to start the machine.

42. The combination with a bed and a presser member movable thereover into different selected operative relations thereto, of a shaft, clutches surrounding said shaft, 10 connections between the shaft and the member operable selectively by means of said clutches, a lever for shifting the clutches to bring one or the other into co-operation with said connections, said lever being operable also to throw the machine into 15 operation to cause the pressure-applying movement of the presser member, and means, comprising a centering device for said lever, for positioning the clutches so that neither 20 are operatively engaged with said connections, said means acting as the lever is depressed to start the machine.

43. The combination with a bed and a presser member movable thereover into 25 different selected operative relations thereto, of a shaft, clutches surrounding said shaft, connections between the shaft and the member operable selectively by means of said 30 clutches, a lever for shifting the clutches to bring one or the other into co-operation with said connections, said lever being operable also to throw the machine into operation to cause the pressure-applying 35 movement of the presser member, and means for positioning the clutches so that neither are operatively engaged with said connections, said means comprising a plate with beveled edges, and a member having a beveled end to co-operate with one or the 40 other of the beveled edges in centering the lever as the latter is depressed to start the machine.

44. A machine for cutting out blanks 45 from sheet material by the use of dies comprising a cutting bed, a presser member mounted for movement over the bed in order that different operative positions therefor may be selected by the operator, power means at all times under the control of the operator for causing said movement of the presser member, manually operable means for controlling said power means, and for throwing the machine into operation to force the die into the work, and means for 50 causing the disconnection of said power means with respect to the presser member as the machine is thrown into operation to force the die into the work.

45. A machine of the class described, 55 comprising co-operation presser members arranged for relative movements at the will of the operator to bring them into different relations to each other, and power means comprising an endwise movable clutch operating shaft at all times under the control of

the operator for causing the said relative movements.

46. In a machine of the class described, presser members relatively movable in a plurality of different paths in different directions, power means for causing relative movements of the presser members along the different paths, and a single means at all times under the control of the operator for controlling the power means to effect successively, at the will of the operator, relative movements of the members along the different paths. 70 75

47. In a machine of the class described, presser members relatively movable in a plurality of different paths in different directions angularly related to each other, power means for causing relative reciprocatory movements of the presser members in the different directions, and a single means at all times under the control of the operator for controlling the power means to effect successively, at the will of the operator, relative movements of the members in the different directions. 80 85 90

48. In a machine of the class described, presser members relatively movable in one path into and out of pressure-applying relation and relatively movable in another path to effect pressure-applying operation, power means for causing relative movements of the presser members along the several paths, and a single means at all times under the control of the operator for controlling the power means to effect successively, at the will of the operator, movements of the members along the several paths. 95 100

49. In a machine of the class described, presser members relatively movable in a direction lateral of each other into and out of pressure-applying relation and relatively movable also in a direction from and toward each other in pressure-applying operations, power means for causing relative movements of the pressure members in both directions, and a single means at all times under the control of the operator for controlling the power means to effect the relative movement of the presser members in a lateral direction and to effect at the will of the operator the relative pressure-applying movement of the presser members. 105 110 115

50. In a machine of the class described, a cutting bed, a presser member movable laterally relatively to the bed, means for causing pressure-applying movement of the presser member, power means for moving the presser member laterally relatively to the bed, and means at all times under the control of the operator for causing said power means to operate and for throwing the machine into operation to cause the application of pressure through the first-mentioned means. 120 125

51. In a machine of the class described, 130

the combination with a cutting bed, of a pressure-applying member movable into various operative relations to the bed, power means at all times under the control of the operator for moving said member, and means independent of the pressure-applying member and controllable by the operator for determining the place over the bed at which pressure shall be applied.

52. In a machine of the class described, a cutting bed, a presser member, means for swinging the presser member over the cutting bed, and a controlling member capable of limited movement to initiate the swinging movement of the presser member over the bed, said controlling member being held stationary during the swinging movement of the presser member and being movable in a direction deviating from the direction 20 in which it has limited movement to initiate the swinging movement of the presser member, to cause the presser member to descend upon the bed.

53. In a machine of the class described, presser members relatively movable laterally into and out of various operative positions determinable by the operator and also relatively reciprocable to effect a pressing operation, power means, and means for controlling said power means to effect relative lateral movement or reciprocation of the presser members, said controlling means being so constructed and arranged that predetermined limited movement thereof in 35 different directions will cause either power reciprocation or lateral movement of the presser members relatively to each other.

54. In a machine of the class described, a work supporting bed, and a presser member relatively movable laterally into and out of various operative positions determinable by the operator and also relatively reciprocable to effect a pressing operation, power means, and means for controlling said power 45 means to effect lateral movement of the presser member over the bed constructed and arranged to be manipulated by the operator for a length of time corresponding to the period of relative movement of the presser members whereby the amount of said relative movement is at all times determinable by the operator.

55. In a machine of the class described, a work supporting bed, and a presser member relatively movable laterally into and out of various operative positions determinable by the operator and also relatively reciprocable to effect a pressing operation, power means, and means for controlling said power 60 means to effect lateral movement of the presser member over the bed so constructed and arranged that the movement of the controlling means for the purpose described is constant regardless of the extent of the rela-

tive lateral movement of the presser members.

56. In a machine of the class described, a work supporting bed, and a presser member relatively movable into and out of operative position and also relatively reciprocable in a different direction to effect a pressing operation, and power means operative to apply sufficient force to the movable presser member to overcome its inertia when it is at rest and actuate it in the desired direction over the bed and constructed and arranged to be under the control of the operator so that the extent of movement so initiated may be determined by the operator.

57. In a machine of the class described, a work supporting bed, and a presser member relatively movable into and out of operative position and also relatively reciprocable in a different direction to effect a pressing operation, and power means organized to be operable to overcome the inertia of the movable presser member in starting it from rest and to impart to it a partial movement only toward operative position over the bed.

58. In a machine of the class described, presser members relatively movable into and out of operative position and also relatively reciprocable in a different direction to the effect a pressing operation, and power means operative to overcome the inertia of the movable presser member in starting it from rest and to impart movement to it in the desired direction and to be disconnectable at the will of the operator so that said presser member may continue in motion under its acquired momentum and may be moved manually into and out of operative position.

59. In a machine of the class described, presser members relatively movable into and out of operative position and also relatively reciprocable in a different direction to effect a pressing operation, and power means constructed and arranged to be operative to overcome the inertia of the movable presser member in starting it from rest and to impart movement to it in the desired direction and to permit the presser member to complete its movement to operative position under its acquired momentum and the direct manual control of the operator.

60. In a machine of the class described, presser members relatively movable into and out of operative position, and also relatively reciprocable in a different direction to effect a pressing operation, and power means constructed and arranged to be operable to move the movable presser member all the way to operative position or only part way thereto, the construction and arrangement being such that the movable presser member may be moved manually into or out of operative position.

61. In a machine of the class described, presser members relatively movable into and out of operative position and also relatively reciprocable in a different direction to effect a pressing operation, power means, and means for controlling said power means to cause power movement of the movable presser member all the way to operative position or only part way thereto, the construction being such that movement of the presser member to operative position may be effected manually.

62. In a machine of the class described, a cutting bed, a presser member, power means for moving the presser member and the bed relatively toward and from each other in cutting operations, power means for moving the presser member laterally over the bed, and a single means for controlling both said power means constructed and arranged for movement in one direction to cause the presser member to move to operative position over the bed, in another direction to cause the cessation of operation of the second mentioned power means, and in still another direction to initiate the operation of the first mentioned power means.

63. In a machine of the class described, upper and lower presser members, power means for moving the upper presser member laterally over the lower presser member, and means for controlling said power means, the construction and arrangement being such that the power means may be disconnected from the movable presser member and may then be used as a brake to stop the lateral movement of the member.

64. In a machine of the class described, presser members relatively movable toward and from each other in pressure applying operations and also relatively movable laterally of each other into and out of operative relation, power means for causing relative lateral movement of the presser members, and means under the control of the operator for stopping said relative lateral movement of the presser members at a point selected either before or after the beginning of the relative lateral movement.

65. In a machine of the class described, presser members relatively movable toward and from each other in pressure applying operations and also relatively movable laterally of each other into and out of operative relation, power means for causing relative lateral movements of the presser members, and a braking means for checking relative lateral movement of the presser members.

66. In a machine of the class described, a work supporting member, a presser member movable toward and from the work supporting bed in pressure applying operations, power means for moving the presser member laterally of the bed into and out of operative position with respect to the work

on the bed, and means under the control of the operator for yieldingly checking the lateral movement of the presser member.

67. In a machine of the class described, a work supporting bed, a presser member movable toward and from the bed in pressure applying operations and movable laterally of the bed into and out of operative position with respect to work on the bed, power means for causing pressure applying operations, power means for moving the presser member laterally of the bed, means for checking the lateral movement caused by the last mentioned power means, and a manually operable member for controlling all three of the last mentioned means.

68. In a machine of the class described, a work supporting bed, a presser member movable toward and from the bed in pressure applying operations and movable laterally of the bed into and out of operative position with respect to work on the bed, power means for causing pressure applying operations, power means for initiating lateral movements of the presser member, frictionally operated means for checking the lateral movements of the presser member, and a manually operable member for controlling the two last mentioned means.

69. In a machine of the class described, a work supporting bed, a pressed member movable toward and from the bed in pressure applying operations and also laterally over the bed into and out of selected operative position, power means for causing lateral movement of the presser member, and manually operable means for exercising direct control of the power means continuously throughout the lateral movement of the presser member.

70. In a machine of the class described, presser members relatively movable toward and from each other in pressure applying operations and also laterally of each other into and out of selected operative position, power means for causing relative lateral movement of the presser members, and manually operable means movable in a given direction for controlling said power means and movable in a direction at an angle to the first direction for causing disconnection of said power means.

71. In a machine of the class described, a work supporting bed, a presser member movable toward and from the bed in pressure applying operations and also laterally over the bed into and out of selected operative position, power means for causing lateral movement of the presser member, and manually operable means movable in a given direction for controlling said power means and movable in a direction at an angle to the first direction for causing disconnection of said power means.

72. In a machine of the class described,

a work supporting bed, a presser member 5
movable toward and from the bed in pressure applying operations and also laterally over the bed into and out of selected operative 10
position, power means for causing lateral movement of the presser member, a manually operable member for controlling said power means, and means for causing disconnection of the power means from the 15
presser member upon movement of the manually operable member in a given direction.

73. In a machine of the class described, a work supporting bed, a presser member 20
movable laterally into and out of various operative positions determinable by the operator and also reciprocable toward and from the bed to effect a pressing operation, and mechanism operative to apply sufficient force to the movable presser member to overcome 25
its inertia when it is at rest and move it in the desired direction over the bed, the construction and arrangement being such that the presser member is continuously under the control of the operator so that the movement 30
of the member to selected operative position may be completed under direct manual control if so desired.

74. In a machine of the class described, a work supporting bed, a presser member 35
movable laterally of the bed and also toward and from the bed in pressure applying operations, and mechanism, comprising a manually operable member, operatively connected with the presser member for moving it laterally of the bed, said manually operable member having a position of rest in which it is yieldingly maintained.

75. In a machine of the class described, a work supporting bed, a presser member 40
movable laterally of the bed and also toward and from the bed in pressure applying operations, mechanism, comprising a manually operable member, operatively connected with the presser member for moving it laterally of the bed, and spring means for yieldingly retaining the manually operable member in its normal position of rest.

76. In a machine of the class described, a work supporting bed, a presser member 45
movable laterally over the bed and also toward and from the bed in pressure applying operations, mechanism operatively connected to the presser member for moving the same laterally of the bed, and a manually operable member movable in a given direction for controlling said mechanism and so arranged as to be operatively disconnectable from said mechanism upon limited movement in the reverse direction.

77. A machine of the class described comprising presser members arranged for relative swinging movements in amounts determined by the operator to bring them into different operative relations to each other, and mechanism at all times under control 60
of the operator for causing said relative swinging movements.

78. In a machine of the class described, a work supporting bed, a presser member 65
movable into and out of operative position over the bed and also reciprocable to effect a pressing operation, and mechanism, comprising a manually operable member, constructed and arranged to be operative to overcome the inertia of the movable presser 70
member in starting it from rest and to impart movement to it in the desired direction and to permit the presser member to complete its movement to operative position under its acquired momentum and the direct manual control of the operator.

79. In a machine of the class described, presser members relatively movable toward and from each other in pressure applying operations and also relatively movable laterally of each other into and out of operative relation, power means for causing relative lateral movements of the presser members, and means for checking relative lateral movement of the presser members.

In testimony whereof I have signed my name to this specification.

HARRISON H. EATON.
